UNITED STATES PATENT OFFICE.

ELLSWORTH A. HAWTHORNE, OF BRIDGEPORT, CONNECTICUT,

ILLUMINATING APPARATUS.

1,361,852.

Specification of Letters Patent. Patented Dec. 14, 1920.

Application filed September 14, 1917. Serial No. 191,346.

To all whom it may concern:

Be it known that I, ELLSWORTH A. HAWTHORNE, a citizen of the United States, and a resident of Bridgeport, in the county of 5 Fairfield and State of Connecticut, have invented an Improvement in Illuminating Apparatus, of which the following description, in connection with the accompanying drawings, is a specification, like characters on the 10 drawings representing like parts.

This invention relates to illuminating apparatus and is more especially though not exclusively concerned with a light concentrating and projecting lamp or searchlight 15 of the class in which provision is made for preventing objectionable glare.

My invention will be best understood by reference to the following description when taken in connection with the accompanying 20 drawings of three specific embodiments thereof, while its scope will be more particularly pointed out in the appended claims.

In the drawings, Figure 1 is a central vertical longitudinal section of an illuminating 25 apparatus embodying my invention;

Fig. 2 is a front elevation of the same;

Fig. 3 is a detail sectional view on an enlarged scale on line 3—3 of Fig. 2;

Fig. 4 is a detail elevation, partly in section, similar to Fig. 3, showing a modification of the light intercepting means;

Fig. 5 is a detail longitudinal sectional view showing another modification of the light intercepting means; and

Fig. 6 is a plan, partly in section, of the parts shown in Fig. 5.

Referring to Figs. 1, 2 and 3 and to the embodiment of my invention which I have selected for exemplification therein, I have 40 shown an illuminating apparatus comprising a suitable casing 7 having a light transmitting opening 8, with a suitable closure therefor such as a glazing 9, and having an interior reflecting surface conveniently in 45 the form of a separate reflector 10 which is preferably a paraboloid of comparatively long focus to project forward in a substantially parallel beam rays of light falling thereon from a substantially focally disposed 50 light source 11, herein in the form of an incandescent bulb disposed in axial alignment with the reflector. This bulb may be and is herein mounted in and carried by an adjustable socket member 12 to permit the 55 same to be moved in and out axially with relation to the reflector. It will be under-

stood that if the socket 12 be adjusted so that the light source 11 is at the focal point of the parabola, the reflected rays will be projected forward in a parallel beam and 60 the lamp will function as a true spotlight, but if, on the other hand, the light source be moved out of focus, a divergent cone of reflected rays will be produced.

In order to permit the use of a long focus 65 reflector without unduly increasing the size of the lamp, the light transmitting opening 8 is placed at some distance from the reflector 10 and a secondary reflector 13 in the form of a spherical zone may be provided, 70 the center of this zone being preferably in the axis of the parabola. In the present example the two reflectors 10 and 13 are connected by a frusto-conical portion 14 which may also be a reflecting surface. If the 75 paraboloid were extended to the position of the secondary reflector 13 the rays would fall thereon at such an angle that they would be of comparatively little value. The rays which would otherwise fall on such extended 80 portion of the paraboloid herein fall on the spherical secondary reflector 13 which returns such rays to the light source and to the primary reflector 10 and the latter then projects them forward through the light 85 transmitting opening.

To prevent the light emanating from the lamp having an objectional glare, I have herein shown light intercepting means in the form of a hollow cylinder or tube 15, preferably disposed substantially co-axially with relation to the reflectors and preferably mounted on the glazing 9. In the present example I have shown the light intercepting means as secured to the glazing by a screw 90 16 and a co-operating nut 17. The cylindrical light intercepting means extends inwardly and surrounds the bulb 11 but is cut away at one side, as at 18, to provide a segmental extension 19 laterally overlying the light source at one side thereof and preferably extending into close proximity to the reflector 10.

The truly cylindrical portion of the light intercepting means 15 outwardly beyond the 95 cut away portion 18 is preferably so proportioned as to intercept all the direct rays of light from the light source 11 which would otherwise pass through the light transmitting opening 8. Thus the light emanating from the lamp consists solely of reflected rays and the intense and concen-

trated direct rays are eliminated, thus obviating much of the glare. The segmental portion 19 overlies the light source at one side thereof and cuts off a portion of the reflector from its rays. A portion of the beam from the light is thus eliminated and only the rays which extend in a certain direction are utilized. Consequently it is possible to provide a beam of light which will not shine above a certain level and which therefore when used on a vehicle will not be projected into the eyes of pedestrians or drivers of other vehicles.

To permit the light source to be screened effectively at one side thereof and at the same time provide for such variations in the distance between the glazing and the reflector as may occur in different lamps, I may make the light intercepting means extensible and in the present example it is in the form of two telescopically arranged tubes 20 and 21. As a means for securing these two tubes in the desired position of adjustment I have herein provided a clamping screw 22 and nut 23, the screw passing through a slot 24 in the tube 20 and the nut 23 being preferably located on the inside of the latter. An inwardly projecting lug 25, formed on the tube 21 and passing through the slot 24, serves as a means to prevent the nut 23 from turning as well as to limit the movement of the tube 20.

In practice it is found that when a light intercepting screen of this general type surrounds or incloses a portion of the light source, so much of the heat is confined by the shield as to have a tendency to overheat the bulb, thus shortening its life, as well as to produce a discoloration of the reflector 10. As a means for permitting the escape of such heat without materially impairing the light intercepting value of the screen, some or all of the latter may be foraminous or reticulated. In the form shown 15 in Figs. 1, 2 and 3, as well as in the form shown in Figs. 5 and 6, a portion only of the screen is foraminous, while in the form shown in Fig. 4 the entire screen is foraminous. In Figs. 1 and 3 it should be observed 20 that the tube 20 is foraminous, while the tube 21 is not. In this form the screen is preferably made of closely woven wire netting which is found to give excellent results. In the form illustrated in Fig. 4 I have shown 25 a screen 26 also formed of similar wire netting.

In the form illustrated in Figs. 5 and 6 I have shown light intercepting means similar in most respects to that illustrated in Figs. 60 1, 2 and 3, except that the adjustable portion is in the form of a segmental plate 27 provided with a multiplicity of perforations 28 to permit the escape of the heat.

Interposed between the end of the tube 65 21 and the glazing 9 is a somewhat yield-

ing washer 29, preferably made of suitable fibrous material such as fiber-board. The interposition of this yielding material between the end of the tubular member and the glazing provides a means to take care of the expansion of the glazing and to prevent the latter from being broken. It also tends to prevent the glass from being broken if the nut 17 should be inadvertently tightened to too great an extent. The washer 75 also tends to strengthen the glazing and to assist in sustaining the weight of the light intercepting means, thus permitting the use of a thinner glazing than would otherwise be possible.

Regardless of the use of light intercepting means for reducing objectionable glare, there is sometimes a point of view where glaring rays will affect the eyes of an observer looking toward the lamp, and under 80 these circumstances the eye is attracted to and dazzled by that portion of the light concentrating means from which the glare emanates. As a means to attract the observer's eye away from the dazzling light rays, I have found that by making the washer 85 29 a dark color, preferably though not necessarily black, it presents a dark spot in the midst of the beam and attracts the eye away from the dazzling rays. In practice 90 it has been found that the provision of the black spot as shown in Fig. 2 has a strong tendency to rest the eye and reduce the 95 harmful effect of the glaring rays.

While I have herein shown and described 100 three forms or embodiments of my invention for illustrative purposes and have disclosed and discussed in detail the constructions and arrangements incidental to these specific applications thereof, it is to be understood 105 that the invention is limited neither to the mere details or relative arrangement of parts nor to the specific embodiments herein shown, but that extensive deviations from the illustrative forms or embodiments of the 110 invention may be made without departing from the principles thereof.

Having described these embodiments of my invention, what I claim and desire by Letters Patent to secure is:—

1. In an illuminating apparatus, the combination of a light source, extensible light-intercepting means associated therewith, including two relatively adjustable members, and clamping means including a screw and nut to secure said members in the desired position of adjustment, and means engaging one side of said nut to hold the same against turning movement.

2. In an illuminating apparatus, the combination of a light source, extensible light-intercepting means associated therewith, including two relatively adjustable members, and clamping means including a screw and nut to secure said members in the desired 130

position of adjustment, and means to limit relative movement of said members and to prevent said nut from turning.

3. In an illuminating apparatus, the combination of a light source, extensible light-intercepting means associated therewith, including two relatively adjustable members, and clamping means including a screw and nut to secure said members in the desired

position of adjustment, one of said members 10 being provided with a slot and the other with a lug projecting into said slot to limit relative movement of said members and to prevent said nut from turning.

In testimony whereof, I have signed my 15 name to this specification.

ELLSWORTH A. HAWTHORNE.
